UNITED STATES PATENT OFFICE.

JOHN A. McCASKEY, OF HAGERHILL, KENTUCKY.

COMBINED CIGAR AND MATCH CASE.

1,215,291.

Specification of Letters Patent.

Patented Feb. 6, 1917.

Application filed January 21, 1916. Serial No. 73,487.

To all whom it may concern:

Be it known that I, JOHN A. McCASKEY, a citizen of the United States, residing at Hagerhill, in the county of Johnson and 5 State of Kentucky, have invented new and useful Improvements in Combined Cigar and Match Cases, of which the following is a specification.

This invention relates to an advertising 10 novelty so constructed as to contain a number of cigars and a quantity of matches.

The primary object of the invention is to provide a device of the class described which may be formed from a blank of material 15 having flaps, one of which is provided with upstruck portions so arranged that when the flap is folded and secured to the case body the front and back of the case provide supplemental compartments upon opposite 20 sides of a main compartment formed within the case by said flap.

Another object of the invention is to provide a blank from which the case is formed with a flap which forms the back of the case 25 and is provided with a supplemental flap having a tongue for insertion in one of the supplemental pockets when the supplemental flap is closing the main compartment and one of the supplemental compartments 30 at the side thereof.

A still further object of the invention is to provide the case with a main compartment which is collapsible so that, cigars when placed in the case are prevented from 35 becoming cracked or broken.

A still further object of the invention is to provide a blank from which the case may be formed having upon certain portions thereof an adhesive material so placed, that 40 the device may be easily assembled after shipment, thus reducing the expense incidental to the shipment of the cases.

With these and other objects in view, the invention resides in the novel combination and arrangement of parts which will be hereinafter described and particularly pointed out in the claims.

The preferred embodiment of the invention has been illustrated in the accompanying drawing, although no restriction is necessarily made to the precise details of construction therein shown, as changes, alterations and modifications within the scope of the claims may be resorted to when so desired.

In the drawing:

Figure 1 is a detail perspective view of a combined cigar and match case constructed in accordance with the invention.

Fig. 2 is a vertical transverse sectional view on the line 2-2 of Fig. 1.

Fig. 3 is a horizontal transverse sectional view on the line 3-3 of Fig. 2.

Fig. 4 is a perspective view showing the blank from which the case is formed partly 65 folded and having a portion thereof broken away.

Fig. 5 is a plan view of the blank from which the case is formed.

Like characters of reference denote corresponding parts throughout the several views in the drawing.

The numeral 1 designates a blank from which the case may be formed and which may be struck from card board or the like 75 which has been pressed and finished to imitate leather, said blank being scored to provide main flaps 2 and 3.

The flap 2 is provided with spaced and vertically extending score lines which divide 80 the main flap 2 into supplemental flaps 5, each of which is provided in its upper marginal edge with a recess 6 and a depressed portion 7 below said recesses, said supplemental flaps 5 having the face thereof in 85 which is formed the depressed portion covered with an adhesive substance as indicated in Fig. 5 in the drawing by the numeral 8.

Extending vertically the entire height of 90 the main flap 2 intermediate the score lines 4 are similar score lines 9 which permit the supplemental flaps 5 when folded along the score lines 4 to provide a main compartment 10 for disposition within the case and 95 to receive therein cigars.

The main flap 3 adjacent flap 2 is provided with horizontally extending score lines 11 which permit the flap 3 to be folded upwardly upon one of the supplemental 100 flaps 5 and to be secured thereto by means of the adhesive substance on said flap so that, the flap 3 which forms the back of the case will overlie one of the depressed portions 7 in a supplemental flap 5 and contact therewith in providing a supplemental compartment at the rear of the case, designated by the numeral 12 for the reception of matches.

The main flap 3 is again scored at its 110

lower end, as indicated at 13 to provide a supplemental flap 14, said flap having a tongue 15 for disposition within a supplemental compartment 16 arranged between the main compartment and front of the case, said compartment 16 being formed by the depressed portion 7 in the other supplemental flap 5 when said flap is connected with the body of the blank from which the case is formed.

It will of course be understood that the blanks are shipped in an unfolded condition so that any desirable advertising matter may be imprinted thereon as the occasion may require and may be folded into the combined cigar and match case by first folding the main flap 2 and securing one of the supplemental flaps 5 formed therefrom to the portion of the blank which forms the front wall of the case. The main flap 3 is then folded and secured to the other supplemental flap 5 thus providing a main compartment within the case having supplemental compartments upon opposite sides thereof for the reception of matches, while the scored lines 9 and 11 permit the collapse of the main compartment when not in use.

The portion of the blank which forms the front of the case is provided near its top with some suitable substance upon which may be struck the matches contained in the supplemental compartments 12 and 16, while the portion of the blank which serves

as the front of the case and the flap 3 assume such position when the blank is folded as to display any advertising matter printed thereon.

From the foregoing statements taken in connection with the accompanying drawing it is at once apparent that a combined cigar and match case has been provided which is simple in construction and inexpensive of manufacture, yet highly efficient in use.

Having thus described the invention what is claimed as new is:

A combined cigar and match case formed from a blank of material having a flap provided with a tongue, a second flap upon the blank foldable upon the body of the blank to provide a collapsible compartment within the case, said last mentioned flap having depressions upon opposite sides of the compartment formed therefrom, one of said depressions coacting with the first mentioned flap to provide a match compartment, and the other depression coacting with a portion of the blank to provide a compartment for the reception of the tongue on the first mentioned flap.

In testimony whereof I affix my signature in presence of two witnesses.

JOHN A. McCASKEY.
